(57) **CLAIM**

The ornamental design for a backing, as shown and described.

DESCRIPTION

FIG. 1 is a top perspective view of a first embodiment for a backing;

FIG. 2 is a bottom perspective view thereof;

FIG. 3 is a front view thereof;

FIG. 4 is a back view thereof;

FIG. 5 is a right view thereof;

FIG. 6 is a left view thereof;

FIG. 7 is a top view thereof;

FIG. 8 is a bottom view thereof;

FIG. 9 is a top perspective view of a second embodiment for a backing;

FIG. 10 is a bottom perspective view thereof;

FIG. 11 is a front view thereof;

FIG. 12 is a back view thereof;

FIG. 13 is a right view thereof;

FIG. 14 is a left view thereof;

FIG. 15 is a top view thereof;

FIG. 16 is a bottom view thereof;

FIG. 17 is a top perspective view of a third embodiment for a backing;

FIG. 18 is a bottom perspective view thereof;

FIG. 19 is a front view thereof;

FIG. 20 is a back view thereof;

FIG. 21 is a right view thereof;

FIG. 22 is a left view thereof;

FIG. 23 is a top view thereof;

FIG. 24 is a bottom view thereof;

FIG. 25 is a top perspective view of a fourth embodiment for a backing;

FIG. 26 is a bottom perspective view thereof;

FIG. 27 is a front view thereof;

FIG. 28 is a back view thereof;

FIG. 29 is a right view thereof;

FIG. 30 is a left view thereof;

(Continued)

FIG. 31 is a top view thereof; and,
 FIG. 32 is a bottom view thereof.
 Broken lines shown in drawings illustrate portions that form
 no part of claimed design.
